UNITED STATES PATENT OFFICE

156,499

CANDLESTICK OR SIMILAR ARTICLE

Felix Friedman, Brooklyn, N. Y.

Application August 28, 1948, Serial No. 148,356

Term of patent 3½ years

(Cl. D48—2)

To all whom it may concern:

Be it known that I, Felix Friedman, a citizen of the United States, residing at Brooklyn, in the county of Kings and State of New York, have invented a new, original, and ornamental Design for a Candlestick or Similar Article, of which the following is a specification, reference being had to the accompanying drawing, forming part thereof.

Fig. 1 is an elevational view of a candlestick showing my new design.

Fig. 2 is a plan view of Fig. 1.

I claim:

The ornamental design for a candlestick or similar article, as shown and described.

FELIX FRIEDMAN.
